UNITED STATES PATENT OFFICE

2,548,137

MACHINE FOR MACHINING TAPERED STUDS

John M. Appleton, Muskegon, Mich., assignor to
Continental Aviation & Engineering Corpora-
tion, Muskegon, Mich., a corporation of Virginia

Application August 6, 1945, Serial No. 609,164

4 Claims. (Cl. 80—8)

1

The present invention relates to the threading of studs or the like and particularly to threading by rolling a suitable blank between suitable straight dies.

Among the objects of the invention is means by which said studs may be tapered for a portion of their length.

The threading of studs by rolling in the threads is quite old and the tapering for a portion of their length is also old but heretofore it has been necessary to use step dies which are expensive, difficult to make, of short life, and many different sets of dies are required due to the length of thread required.

Another object of the present invention is, therefore, to obtain the desired taper while making use of a conventional die without the step.

Still another object is means which may be adjusted to provide a tapered portion of two, three or more threads as desired.

Other objects and advantages will readily occur to those skilled in the art upon reference to the following description and the accompanying drawings in which

Fig. 1 is an end elevation, with parts in vertical section, of the active parts of the thread rolling machine.

Fig. 2 is a plan view of the same.

Fig. 3 is an enlargement of the sectioned portion of Fig. 1, showing the parts in a different position.

Fig. 4 is an elevation of the valve control, indicating its action.

Fig. 5 is a partial end view of the machine.

In the drawings, there are shown only those parts of the threading machine which act directly on a stud to be threaded, it being understood that a suitable base or frame and means for actuating the movable parts will be used. These latter being no part of the invention, are not being shown.

As in conventional machines for threading, a suitable blank 10 is rolled between a pair of straight dies 11 and 12 to press the threads into the blank 10. This is done by holding the die 12 against longitudinal movement while the die 11 is carried on a slide 11A which is conventional except as will be described later.

The die 12, however, instead of being mounted in a fixed holder, as is usual, is carried in a cradle member 15, having its rear face arc shaped with the center of the arc at a point between the two dies and approximately at half the height of the dies.

This cradle member 15 is supported in a corre-

2

sponding curved seat in the base 16 and is held against displacement by end plates 17 screwed to the ends of the base 16 and curved concentrically with the cradle and seat, the ends 17A of the plates 17 extending over the ends of the cradle 15 and in suitable curved seats 15A therein.

The central portion of the seat for cradle 15 is cut away to provide a recess 19 for the reception of a rearwardly extending arm 20 fixed to or formed integrally with the cradle 15, the recess 19 being bridged by a plate 21 which overlies the arm 20, sufficient space being provided to permit a small vertical movement of the arm.

This vertical movement is adjustably limited by suitable stop screws of which three are shown. The screws 22 are fixed in the plate 21, extending therethrough and acting against the arm 20 or a suitable inserted hardened button 22A.

The stop screw 23 is fixed in the arm 20 and extends loosely through plate 21 above which the nuts 23A act as an adjustable head to limit the downward movement of arm 20.

The cradle 15 also is provided with an upwardly extended boss 25 having a bore 26 extending horizontally therethrough from front to rear at the ends of which the boss is faced with hardened washers or plates 27.

Through the bore 26 extends a rod 30 of somewhat smaller diameter than the bore and carrying at the end of the latter a collar 31, which is provided with an angular face 31A contacting the adjacent face plate 27, the apex line of the angle being horizontal and extending across the plate 27 at substantially its center.

These collars 31 are provided with suitable set screws 31B to prevent rotation but are fixed against longitudinal movement on the rod 30 by, in one case, a suitable shoulder 32 and, in the other case, nuts 33.

The rod 30 extends rearwardly and is functionally a part of the piston rod extending into a double acting pressure cylinder 35 to the ends of which lead conduits 36 and 37 from a valve 38 operable by a vertically movable stem 39. Valve 38 is carried on a suitable stationary portion 40 of the machine and the stem 39 is actuatable upward by a plunger 39A mounted in a suitable bracket 40A, the plunger 39A carrying a roller 39B acting as a cam follower and prevented from turning by means of a suitable screw 40B in bracket 40A. Downward movement of the plunger and stem is accomplished by suitable spring means (not shown).

Carried on the movable die holder 11A is a cam 45 so positioned with respect to the die that, at a

suitable point before the end of die travel, the sloping surface 45A of the die strikes the follower 39B and lifts the valve stem. The return movement of the slide of course permits the downward movement of the valve stem.

In the operation of the machine, fluid, preferably air, under pressure passing through valve 38, enters cylinder 35 through conduit 37 and maintains the die 12 in the position of Fig. 1. As the operation of threading nears completion, the cam 45 acting on valve 38 causes the pressure in cylinder 35 to be transferred from the rear end to the front end through conduit 36 and thereby the cradle 15 and die 12 to be tilted as in Fig. 3.

Return movement of slide 11A permits the valve 38 to restore the pressure to conduit 37 and return the cradle 15 to the position of Fig. 1.

I claim:

1. In a threading machine, a longitudinally reciprocable member, a stationary member, said members having faces normally parallel to each other, but in spaced relation, a threading die mounted in each of said faces, said dies being in opposed parallel relation and spaced from each other, means for moving an edge portion of one of said dies toward the other die and means actuated by said reciprocable member during the reciprocation for causing such die movement.

2. In a thread rolling machine having a reciprocable member and a stationary member, a die mounted in each of said members, one of said dies having a fixed mounting, a cradle member carrying the other of said dies, said cradle being rockable on an axis parallel to the movement of reciprocation, and means actuated by said reciprocable member to cause said cradle to assume a position wherein its die is tilted with respect to the other die.

3. In a thread rolling machine, a pair of dies of which one is mounted for reciprocation past

the other, means for mounting one of said dies, said means consisting of a die holding member having an arcuate rear face, the axis thereof being parallel to the line of reciprocation, an arcuate seat for said member, and means for moving said member on said seat, said moving means comprising a fluid pressure cylinder and piston with the piston operatively connected to said member, a valve adapted to admit pressure fluid alternately to the ends of said cylinder, and valve actuating means carried by the reciprocable die carrying element.

4. In a thread rolling machine, a reciprocable slide member, a die mounted thereon, a fixed member, a die carried by said fixed member and held normally in opposed relation to the first die, mounting means for said second die comprising a member partially rotatable about an axis parallel to the line of reciprocation, means for effecting such partial rotation comprising a fluid motor, a control valve therefor and a cam for actuating said valve, said cam being mounted on said reciprocable member adjacent the end of its movement of reciprocation.

JOHN M. APPLETON.
